UNITED STATES PATENT OFFICE.

ABRUZZO MICHELE, OF PITTSBURG, PENNSYLVANIA, ASSIGNOR OF ONE-HALF TO BERNARD GASPARRO, OF PITTSBURG, PENNSYLVANIA.

REPEATING FIREARM OR RIFLE.

No. 819,153.

Specification of Letters Patent.

Patented May 1, 1906.

Application filed September 28, 1904. Serial No. 226,340.

To all whom it may concern:

Be it known that I, ABRUZZO MICHELE, a citizen of Italy, residing at Pittsburg, in the county of Allegheny and State of Pennsylvania, have invented certain new and useful Improvements in Repeating Firearms or Rifles; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to an improved repeating firearm or rifle; and it consists in the certain details of construction and combination of parts, as will be fully described hereinafter.

20 In the accompanying drawings, Figure 1 is a side sectional elevation of the working parts of my improved firearm, the rifle-barrel being partly broken away, the said view being constructed and arranged in accordance with my invention. Fig. 2 is a sectional end view of the same, the said section being taken on the line $\alpha-\alpha$ of Fig. 1. Fig. 3 is a fragmentary sectional view showing the breech mechanism and means for turning the 25 cartridge after same has been removed from the carrying mechanism; and Fig. 4 is a top plan view thereof, partly shown in section.

To put my invention into practice, I provide a hollow stock 1 of a suitable size and 35 form of construction and fit the same with a rifle-barrel 2 and mechanism for operating the breech-block 5 to be hereinafter described. Arranged within the stock 1 is a spring-actuated mechanism consisting of the 40 spring 11, mounted in a frame 13, and a series of gearing 12, adapted to operate a sprocket-wheel 8 at the front and a similar wheel 14 at the rear. Operating over these two sprocket-wheels 8 and 14 and also a like wheel 14' is a 45 belt 10, carrying a number of spring-holders 25, in which cartridges 26 are placed, the said holders being arranged at regular intervals the entire length of said belt, as will be seen by reference to Fig. 1 of the drawings. The 50 shafts of the two rear sprocket-wheels 14 and 14' are each fitted with small sprockets connected the one with the other by a chain 16 to insure uniform movement, the said shafts being driven by gearing 17 and 18 from the

spring 11. At the forward end of the belt 10 55 is arranged a lever 19, which is connected by a rod 21 to a crank-disk 22, the object of which is to lift the cartridge 26 from the holders 25 one after the other as they are presented by the forward movement of the belt 60 10. This lever 19 has a rocking movement on a pivot 19', and immediately after its hooked rear end lifts the cartridge from the holders 25 a bar 23, having a reciprocatory movement, engages the loaded end thereof 65 and starts that end down the inclined upper face of said lever 19. As said cartridge moves forward the movement of its cap end will be retarded by engagement with a rib 20'. The forks 20 of said lever at this period 70 are inclined and the cartridge slides endwise down the same past the breech-block 5. This breech-block is slidably mounted by a cross-bar 31 in grooved guides 32 on opposite sides of the casing, and to said cross-bar is 75 pivotally connected the trigger 4. When the trigger is in its forward position under the action of the spring 33, the cross-bar 31 is in the lowest portion of the curved guides 32 and the breech-block out of the path of the 80 cartridge as it slides down the forks 20. Upon forward movement of the trigger the cross-bar lifts in guides 32, raising the breech-block between forks 20 and bringing the firing-pin 34 into line with the cartridge for 85 exploding the latter by any suitable means. (Not shown.) Of course it will be observed that as the breech-block 5 is moved forward it forces the cartridge into the barrel 2.

Various modifications and changes may 90 be made in the details of construction without departing from the spirit of the invention. Therefore I do not wish to confine myself to that shown and described.

Having thus described my invention, what 95 I claim, and desire to secure by Letters Patent, is—

1. In a firearm of the nature described, the combination comprising the spring-actuated mechanism for rotating sprockets, of a 100 belt or strap engaging said sprockets to give the same a forward continuous movement, a lever for removing cartridges attached to said belt or strap one at a time, and delivering the same to the loading and firing mechanism of the firearm, as described.

2. In a firearm, a barrel, an endless cartridge-conveyer operated by spring-actuated

mechanism, means for extracting the cartridges therefrom, means for turning said cartridges, and means for feeding said cartridges to said barrel.

3. A firearm, in combination with the barrel, of an endless cartridge-carrier operated by spring-actuated mechanism, pivoted means by which said cartridges are extracted from said carrier, and means operating within said pivoted means for feeding said cartridges into said barrel.

4. A firearm, in combination with the barrel, of an endless cartridge-conveyer operated by spring-actuated mechanism, a cartridge-extractor, means in conjunction therewith for turning the cartridges, and a vertically-moving means for transferring the cartridges from said extractor into the barrel.

5. A firearm, in combination with the bar-

rel, of an endless cartridge-conveyer operated by spring-actuated mechanism, means for extracting the cartridge therefrom, and a vertically and horizontally movable breech-block for feeding the cartridge from said extracting means to said barrel.

6. In a firearm, in combination with the barrel, of an endless cartridge-conveyer operated by spring-actuated mechanism, a pivoted extractor and turner a breech-block operating through said pivoted extractor, and means whereby said breech-block is moved vertically and horizontally.

In testimony whereof I affix my signature in presence of two witnesses.

ABRUZZO MICHELE.
